COMBINED CUP AND DRINKING TUBE HANDLE

Meyer Saffer, Jamaica, N.Y.

Application May 23, 1958, Serial No. 51,049

Term of patent 14 years

(C.I. D44—9)

FIG. 1.

FIG. 3

FIG. 2

Figure 1 is a perspective view of a combined cup and drinking tube handle, showing my new design;

Figure 2 is a front elevational view thereof;

Figure 3 is a cross-section view thereof.

The dominant features of my design are shown in full lines.

I claim:

The ornamental design for a combined cup and drinking tube handle, substantially as shown and described.
